(57) **CLAIM**

The ornamental design for a housing for a convertible blower/vacuum, as shown.

DESCRIPTION

FIG. 1 is a left front perspective view of a housing for a convertible blower/vacuum in accordance with one embodiment of the present invention;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.
